DESIGN FOR A MERRY-GO-ROUND

Clifford I. Sweet, Delphos, Ohio, assignor to The
Delphos Bending Company, Delphos, Ohio, a
corporation of Ohio

Application July 11, 1934, Serial No. 52,532

Term of patent 14 years

To all whom it may concern:

Be it known, that I, CLIFFORD I. SWEET, a citizen of the United States, residing at Delphos, Van Wert County, Ohio, have invented a new, original, and ornamental Design for a Merry-Go-Round, of which the following is a specification, reference being had to the accompanying drawing, forming part thereof.

The single figure of the drawing is a perspective view of a merry-go-round embodying my new design.

I claim:

The ornamental design for a merry-go-round, as shown.

CLIFFORD I. SWEET.
